REINFORCED LINK FOR ANTI-SKID CHAINS

John R. Reyburn, Fairfield, Conn., assignor to
 American Chain & Cable Company, Inc., New
 York, N. Y., a corporation of New York

Application November 10, 1939, Serial No. 303,751

4 Claims. (Cl. 152—243)

This invention relates to improvements in reinforced links for anti-skid tire chains. This application is a continuation in part of my co-pending application Ser. No. 132,279 filed March 22, 1937.

A broad object of the present invention is to provide a cross chain with improved reinforced tread links having caulks secured thereto in such position as to increase the overall width of the links and present projections adapted to dig into slippery surfaces so as to increase traction and prevent skidding. This broad object as disclosed in said application is accomplished preferably by providing a link with downwardly and outwardly flaring diverging lugs which extend downwardly below the road engaging surfaces of the link and outwardly beyond the sides of the link.

A specific object of this invention is to provide an improved construction in which the link with which the caulks are associated is provided with side strands which have those portions to which the caulks are secured, extending and lying in the same horizontal plane.

More specifically it is an object of this invention to provide a link of the curb type having portions of its side strands lying in the same horizontal plane, with downwardly diverging lugs which project downwardly below the road engaging lobes of the link and outwardly beyond the sides of the link.

Another object of this invention is to provide an improved reinforcing element in which the caulks are integrally connected by a strap which may be of considerably less cross sectional area than that of the caulks and in which the strap and the caulks are preferably so related as to form a seating surface at their juncture to seat on the side strands of the link.

Other objects of the invention will appear from the following description taken in connection with the drawing in which—

Fig. 1 is a side elevational view of a reinforced link disclosing one form of my invention;

Fig. 2 is a cross section of the link shown in Fig. 1 on the line 2—2 of Fig. 1;

Fig. 3 shows a link provided with a modified form of reinforcement;

Fig. 4 shows another modified form of reinforcement applied to a link;

Fig. 5 shows in perspective a blank from which the reinforcement disclosed in Fig. 4 may be formed;

Fig. 6 shows another modified form of reinforcement; and

Fig. 7 shows the manner of applying a reinforcement such as disclosed in Fig. 6 to a curb link having straight side strands oppositely inclined throughout their lengths.

Referring first to Figs. 1 and 2 of the drawing, I disclose in these figures a link 10 of the general curb type provided with end connecting loops 11 which comprise tire and road engaging lobes and with side strands 12 which instead of being inclined throughout their entire length are provided with parallel portions which lie in the same horizontal plane to which are secured downwardly and outwardly flaring caulks 13 which extend downwardly below the road engaging lobes of the link and outwardly beyond the sides of the link and present their free edges 14 parallel to the road. By means of this construction the road engaging lobes are protected against wear by the caulks and if the caulks are made of the general rectangular form disclosed they will present a large amount of material to be worn away before there is any appreciable wear on the road engaging lobes of the link.

As disclosed in Fig. 3, the reinforcement may comprise a trough shaped member 15, the ends of which constitute downwardly diverging caulks 17, and the intermediate portion 18 of which constitutes a strap connecting these caulks and the side strands of the link. In this figure the trough shaped member is disposed on top of the link, that is, on the tire side of the link, and is welded to the side strands 12 of the link at the juncture of the caulks 17 and the connecting strap 18. This provides for an extended welded surface 19 between the reinforcement and the link.

In Fig. 4 I have disclosed a reinforcement 20 applied to the link in the same general way as disclosed in Fig. 3. This reinforcement may be formed from the blank shown in Fig. 5. It comprises end portions 21 which constitute the caulks and which may be of relatively large cross section separated by a wide groove 22 and connected by a thin portion 23, the thin portion constituting a strap connecting the caulks 21. By rounding the surface at the juncture between the strap 23 and the caulks 21 to generally conform to the curvature of the side strands of the link, I am able to increase the length of the welding surface between the side strands and the reinforcement and to locate at least a portion of the material of the caulks in line with portions of the strands so that part 55 of the thrust on the caulks will be transmitted

directly to the strands, thus reducing the tendency of the thrust to shear the weld between the caulks and the strands.

In Fig. 6 I have disclosed a reinforcement which may be made from the blank disclosed in Fig. 5 but in this figure the trough shaped member is placed on the bottom of the link and welded thereto, the reinforcement disclosed in Fig. 5 being bent in trough form in an opposite direction from that disclosed in Fig. 4. In this figure I have indicated the reinforcement as 20a provided with caulks 21a separated by a channel 22a and connected by a thin strap portion 23a, the weld between the reinforcement and the side strands of the link being indicated at 24a. In this construction the upward thrust on the caulks is transmitted substantially entirely to the side strands, thus relieving the weld from shearing stresses, and the strap portion 23a being located substantially tangentially to the bottom faces of the strands bridges the caulks at a point where the bridging connection is most effective. This strap portion 23a not only effectively prevents the spreading of the side strands of the link but it also prevents spreading of the caulks 21a.

The reinforcements disclosed in Figs. 3, 4, 5, and 6 may be welded to curb links in which the side strands are oppositely inclined as indicated in Fig. 7. In this figure a curb link is indicated generally at 30 and is provided with tire engaging lobes 31, ground engaging lobes 32, and oppositely inclined side strands 33 and 34. The reinforcement which I have here indicated as 20b comprises a strap portion 23b and caulks 21b. This reinforcement is preferably twisted before it is welded to the link to cause the junctures between the strap portion 23b and the caulks 21b to fit the oppositely inclined side strands of the link to facilitate welding the reinforcement to the side strands of the link.

While I have disclosed several forms of my invention, it is to be understood that these forms are susceptible to modification and that I reserve the right to all such changes as fall within the principles of the invention disclosed and the scope of the appended claims.

I claim:

1. In an anti-skid chain, a tread link of the curb type including side strands and tire and

road engaging lobes, substantial portions at least of said side strands extending and lying in the same horizontal plane, and caulks arranged normal to said portions of said side strands, said caulks diverging and projecting downwardly below the road engaging lobes and laterally beyond the sides of the link.

2. In an anti-skid chain, a chain link comprising a pair of side strands connected at each end to form an elongated closed link, and an inverted trough shaped member disposed on the bottom side of the link and having its side walls projecting downwardly below the ground engaging lobes of the link and outwardly beyond the sides of the link and welded to said side strands, the bottom wall of said member being disposed substantially tangentially with the bottom surfaces of said side strands, said side walls and bottom wall being connected by surfaces conforming to the adjacent surfaces of the side strands and having their outer edges lying in a plane extending through the side strands.

3. In an anti-skid device, a link comprising side strands and end connecting loops, and a trough shaped reinforcement provided with diverging side walls of substantial thickness and a bottom wall of less thickness, said side walls and bottom wall being connected by surfaces conforming to the transverse shape of the adjacent faces of the side strands and having one of their edges lying in the plane of one face of the bottom wall and their other edges lying in a plane extending through the side strands, said reinforcement being welded to said side strands along said curved surface at the junctures of said bottom and side walls.

4. In an anti-skid chain, a tread link of the curb type comprising oppositely inclined side strands and tire and road engaging lobes, and an inverted trough shaped member disposed on the lower face of said link and having side walls of substantial thickness and a bottom wall of less thickness and having surfaces between said bottom and side walls conforming to the transverse shape and the inclination of said side strands, the outer edges of said surfaces lying in planes passing transversely through said side strands at a point above said side strands and welded to said side strands.

JOHN R. REYBURN.

CERTIFICATE OF CORRECTION.

Patent No. 2,280,717.

April 21, 1942.

JOHN R. REYBURN.

It is hereby certified that error appears in the printed specification of the above numbered patent requiring correction as follows: Page 2, second column, lines 48 and 49, strike out "and welded to said side strands" and insert the same after "strands" and before the comma, line 45, same claim; and that the said Letters Patent should be read with this correction therein that the same may conform to the record of the case in the Patent Office.

Signed and sealed this 23rd day of June, A. D. 1942.

(Seal)

Henry Van Arsdale,
Acting Commissioner of Patents.
